US00D347063S

United States Patent [19]

Ariyoshi et al.

[11] Patent Number: Des. 347,063

[45] Date of Patent: ** May 17, 1994

[54] MAGNETIC RESONANCE IMAGING SCANNER

[75] Inventors: **Tsukasa Ariyoshi**, Kokubunji; **Shigeki Masatsugu**, Sayama; **Tatsuo Murai**, Machida; **Hiroyuki Kuriyama**, Yokohama; **Atsuo Yoshida**; **Atsuhiko Urushihara**, both of Kokubunji; **Tadashi Sube**, Kodaira; **Kazunori Yanagisawa**, Higashiyamato; **Atsushi Katayama**, Kokubunji; **Shyoji Kondo**; **Yoshiki Igarashi**, both of Katsuta, all of Japan

[73] Assignee: **Hitachi, Ltd.**, Tokyo, Japan

[**] Term: **14 Years**

[21] Appl. No.: **883,969**

[22] Filed: **May 15, 1992**

CLAIM

The ornamental design for a magnetic resonance imaging scanner, as shown.

DESCRIPTION

FIG. 1 is a front, top and right side elevational perspective view of a magnetic resonance imaging scanner showing our new design;

FIG. 2 is a front elevational view thereof;

FIG. 3 is a right side elevational view thereof, the left side elevational view being identical thereto;

FIG. 4 is a rear elevational view thereof;

FIG. 5 is a top plan view thereof; and,

FIG. 6 is a bottom plan view thereof.

FIG. 1

FIG. 2

FIG. 3

FIG. 4

FIG. 5

FIG. 6
